Inventor:
Frederick W. Hudson

UNITED STATES PATENT OFFICE.

FREDERICK W. HUDSON, OF LEOMINSTER, MASSACHUSETTS.

APPLE-PARER.

SPECIFICATION forming part of Letters Patent No. 252,670, dated January 24, 1882.

Application filed May 12, 1881. (Model.)

To all whom it may concern:

Be it known that I, FREDERICK W. HUDSON, of Leominster, in the county of Worcester and Commonwealth of Massachusetts, have 5 invented certain new and useful Improvements in Apple-Paring Machines; and I do hereby declare that the following is a full, clear, and exact description of the same, reference being had to the accompanying drawings, forming 10 a part of this specification, and in which—

Figure 1 represents a top or plan view of one of my aforesaid improved apple-parers. Fig. 2 represents a front side view of said apple-parer, looking in the direction indicated 15 by arrow 1 of said Fig. 1, when attached to its support F for use. Figs. 3 and 4 represent, upon an enlarged scale, different views of portions of the apple-parer, which will be herein-after more fully described; and Fig. 5 represents a section through the parts shown in 20 Fig. 3, taken on line A B, looking in the direction indicated by arrow 2 of said Fig. 3.

To enable those skilled in the art to which my invention belongs to make and use the 25 same, I will proceed to describe it more in detail.

In the drawings, C represents the framework of the machine, which is formed with a bend, D, and provided with a thumb-screw, E, 30 so that it may be secured to the edge of a table or support, F, as represented in Fig. 2.

G represents the grooved rotating table of the machine, which is arranged to turn on a pivot, H, secured in the part I of frame C. 35 Upon said table G are arranged the parer J and throwing-off arm K, which may be constructed, arranged, and operated in the ordinary manner, the motion of the parer being governed by its end passing over the cam-surface I' of the part I, while the motion of the throwing-off arm is governed by the part L formed upon said arm passing over the surface M of frame C. Both of said parts J and K are sprung back and held against their respective 40 cam-surfaces by means of spiral springs N and O. The knife P is secured to the parer J by means of a screw, a.

Table G is provided entirely around its outer surface with cogs or teeth b by means of a 45 bevel-gear, Q, which works in said teeth. Bevel-gear Q is formed upon the point of the

cone-shaped frame R, which turns upon a journal, c, secured in frame C. Upon the outer larger end of said cone-frame R is formed a cog-gear, R', and hand crank or lever S, and 55 by means of which crank the machine is operated. Cog-gear R' is for the purpose of operating a small spur-gear, T, which is secured to the end of a shaft, U, thus turning the apple-parer V, which is secured to the other end of 60 said shaft U, shaft U being arranged to turn in the part W of frame C.

From the foregoing description it will be seen that table G is turned so as to operate apple-parer J and throwing-off arm K, and also 65 that the apple-holder V is turned by the operation of hand-crank S, as before explained, table G being turned in the direction indicated by arrows 3 3, Figs. 1 and 2.

In the drawings the several parts of the machine are represented in the positions which they occupy just as the apple-parer J commences the operation of paring the apple which is to be placed on the rotating holder V. During the first revolution of the apple-holder V, 75 after the parer J first strikes the base of the apple, the knife P is held against the base or stem end of the apple by the combined action of spring N and cam X, as hereinafter described, so as to pare the same close up to said 80 stem.

Table G is fitted loosely upon its fulcrum a, whereby a wobbling motion can be imparted to it by means of a cam, X, which is formed upon the under side of said table G, as represented in Figs. 4 and 5. Cam X is made in ring form and projects from the back side of table G, and is made to project farthest from the back surface of the table at the point e, and which point is upon the same side of table 90 G as the apple-parer J. Consequently the tipping of table G causes the knife of the parer J to move toward the fork which supports the apple, thereby compensating for the withdrawal of the knife from the fork, caused by 95 the rotation of the table, until one turn of the apple has been made, and by which operation the flat or stem end of the apple can be pared more perfectly, and that, too, close up to the fork, than by machines heretofore in use.

The combination of the cone-shaped part R, as before described, enables me to dispense

with one of the gears usually employed upon an apple - paring machine, thereby not only cheapening the manufacture of said machines, but also enabling them to be made more durable and compact in form, while by arranging the table so that it can be tilted, as before described, the apple can be pared very nicely and evenly and entirely up to its stem or the end which is forced onto the fork-holder V.

10 Having described my improvements in apple-paring machines, what I claim therein as new and of my invention, and desire to secure by Letters Patent, is—

1. The combination, with the cone frame R,

of gears Q and R', for operating geared table G and gear T, substantially as and for the purposes set forth.

2. The combination of the geared table G, provided with an enlarged socket, and the elevated head of the pivot H of said table, 20 with the cam X and frame I, whereby the knife pivoted to the geared table is actuated, substantially as and for the purpose described.

FREDERICK W. HUDSON.
